(57) **CLAIM**

The ornamental design for a rib pet treat, as shown and described.

DESCRIPTION

FIG. 1 is a front, top and right side perspective view of a first embodiment of a rib pet treat according to the new design; FIG. 2 is a front, bottom and right side perspective view of the embodiment of FIG. 1;

FIG. 3 is a front view of the embodiment of FIG. 1;

FIG. 4 is a back view of the embodiment of FIG. 1;

FIG. 5 is a left side elevation view of the embodiment of FIG. 1;

FIG. 6 is a right side elevation view of the embodiment of FIG. 1;

FIG. 7 is a top plan view of the embodiment of FIG. 1;

FIG. 8 is a bottom plan view of the embodiment of FIG. 1;

FIG. 9 is a front, bottom and left side perspective view of a second embodiment of a rib pet treat according to the new design;

FIG. 10 is a back, top and left side perspective view of the embodiment of FIG. 9;

FIG. 11 is a front view of the embodiment of FIG. 9;

FIG. 12 is a back view of the embodiment of FIG. 9;

FIG. 13 is a bottom plan view of the embodiment of FIG. 9;

FIG. 14 is a top plan view of the embodiment of FIG. 9;

FIG. 15 is a left side elevation view of the embodiment of FIG. 9; and,

FIG. 16 is a right side elevation view of the embodiment of FIG. 9.

The broken lines in FIGS. 9-12 and 14-16 illustrate portions of the rib pet treat that form no part of the claimed design.

1 Claim, 12 Drawing Sheets
